UNITED STATES PATENT OFFICE.

ALBERT J. WEATHERHEAD, OF CLEVELAND, OHIO.

DESIGN FOR A VENT-VALVE.

SPECIFICATION forming part of Design No. 16,886, dated August 31, 1886.

Application filed June 28, 1886. Serial No. 206,544. Term of patent 14 years.

To all whom it may concern:

Be it known that I, ALBERT J. WEATHERHEAD, a citizen of the United States, residing at Cleveland, in the county of Cuyahoga and State of Ohio, have invented a certain new and original Design in Vent-Valves; and I do hereby declare that the following is a full, clear, and exact description of the invention, which will enable others skilled in the art to which it appertains to make and use the same.

My invention relates to a design for vent-valves; and it consists in the cylindrical and conical form of the interior and exterior of the valve, as shown and described.

In the accompanying drawings, Figure 1 shows a plain elevation of the exterior of the valve. Fig. 2 is a vertical section thereof through the center in one direction, and Fig. 3 a vertical section in another direction and at right angles to the line of Fig. 2.

The form of valve constituting my design embraces the following distinguishing and characteristic features, viz: Viewing the valve in elevation, as shown in Fig. 1, it presents an exterior defined by plain cylindrical sides *a* and a conical end, *b*. Interiorly, as seen in Figs. 2 and 3, the valve shows, first and most conspicuously, an opening extending from its

lower end to a point above its vertical center, having cylindrical outlines of different diameters, as at *c* and *d*, with a horizontal line intermediate of said cylindrical outlines and at right angles thereto. The upper portion of the opening *c* is conical, and transversely above the cone is an interior open slot shaped in the form of an inverted V along its upper and lower edges, respectively, and having straight ends and plain parallel sides.

It will be observed that a valve fashioned according to this description and as revealed in section in Fig. 2 shows a series of conical lines, 1 2 3, about equidistant apart.

Having thus described my invention, what I claim as new, and desire to secure by Letters Patent, is—

In a design for a vent-valve, the form of the same as shown and described, and consisting of the plain cylindrical side and conical-shaped end of the exterior and the shape of the interior, which is defined by cylindrical and conical outlines *c d e*, as described.

ALBERT J. WEATHERHEAD.
